UNITED STATES PATENT OFFICE

166,499

COMBINATION HANDLE AND LOCK UNIT

Earl F. Rutan, Pound Ridge, N. Y., assignor to
The Mosler Safe Company, Hamilton, Ohio, a
corporation of New York

Application January 2, 1952, Serial No. 17,886

Term of patent 14 years

(Cl. D69—1)

To all whom it may concern:

Be it known that I, Earl F. Rutan, a citizen of the United States of America, residing at Pound Ridge, county of Westchester, State of New York, have invented a new, original, and ornamental Design for a Combination Handle and Lock Unit, of which the following is a specification, reference being had to the accompanying drawing, forming a part thereof.

Fig. 1 is a front elevational view of a combination handle and lock unit with a safe door shown in broken lines for illustrative purposes, embodying my new design;

Fig. 2 is an enlarged view in front elevation of the design shown in Fig. 1;

Fig. 3 is an enlarged top plan view thereof; and

Fig. 4 is a view in section taken on line IV—IV of Fig. 2.

I claim:

The ornamental design for a combination handle and lock unit, as shown and described.

EARL F. RUTAN.
